UNITED STATES PATENT OFFICE.

JOSEPH W. McCANN, OF WASHINGTON, DISTRICT OF COLUMBIA.

REVERSIBLE COVER AND DETACHABLE FASTENER THEREFOR.

1,318,094.

Specification of Letters Patent.

Patented Oct. 7, 1919.

Application filed April 10, 1919. Serial No. 288,918.

To all whom it may concern:

Be it known that I, JOSEPH W. McCANN, a citizen of the United States, and a resident of the city of Washington, District of Columbia, have invented a certain new and useful Improvement in Reversible Covers and Detachable Fasteners Therefor, of which the following is a specification.

This invention relates broadly to portable field kits and the like such as employed at the present time by field officers on duty with troops. More particularly, the invention is directed to a reversible cover for kits of this nature provided with a readily detachable fastening so that the same may be removed from its closed position on the box and inverted to present a precision surface for field use.

The principal object of the present invention is to provide a detachable fastening for lids of this construction which will readily slip into locking engagement with a bearing member formed on the box, and readily removable therefrom to permit the lid to be moved to different positions.

A further object of the present invention is to provide a detachable fastening of this type which will serve as a joint to prevent the entrance of water to the interior of the kit and, at the same time, constitute a precision edge which may be used in conjunction with the precision surface formed on the lower side of the cover.

A still further object of the present invention is to provide a detachable connection of the type referred to which may be secured in operative position within the kit so that when the cover is secured in position it will be impossible to remove the same.

These and other objects, together with their attendant advantages, will be apparent as the invention becomes better understood by reference to the accompanying specification and drawings forming a part thereof, in which—

Figure 1^a is a perspective view of the exterior of a field kit embodying my invention.

Fig. 1 is a perspective view showing the interior construction of the kit with the cover partially removed therefrom.

Fig. 2 is a perspective view of the kit showing the cover in inverted position.

Fig. 3 is an enlarged detail view of the

interior of the kit showing a bearing member in position therein. 55

Fig. 4 is a longitudinal section on the lines b—b of Fig. 3 looking in the direction of the arrows.

Fig. 5 is an enlarged sectional view on the lines a—a of Fig. 4 looking in the direction of the arrows. 60

Fig. 6 is a perspective view of a preferred embodiment of my detachable locking connection. 65

Figs. 7, 8 and 9 are perspective views of modified forms of detachable connections.

Fig. 10 is a detail view of a modified form of connection adapted for use on the exterior of the kit. 70

Referring more particularly to the drawings, I have shown a field kit or box 1 having a reversible cover 2, which may be locked in position on the box by means of a suitable lock 4. The box 1 is provided preferably 75 with a suitable inner lining 5 which projects nearly to the upper edge of the box and is so constructed that a weather groove or channel 6 is formed between the box and the inner lining. The groove 6 may be 80 formed by spacing the inner lining from the interior surface of the box, or by forming vertical grooves or cut-away portions 7 in the sides and ends of the box.

The reversible cover 2 is provided on its 85 under side with a precision surface 8 which may comprise a drawing board or the like. The precision surface preferably projects a considerable distance from the under side of the cover and is of such size that when 90 the cover is in its normal closed position the edges thereof coöperate with the inner lining to form a tight joint and assist the lock in preventing displacement of the cover. If desired, the upper side of the cover may be 95 provided with a projecting member 9, corresponding in configuration to the precision surface 8, for the purpose of preventing lateral displacement of the cover when in its inverted position. When such a construction is employed, it is possible to use the precision surface, as indicated more particularly in Fig. 2 of the drawings, without fear of the same moving about. 100

The detachable locking construction for 105 the reversible cover preferably comprises an angular member 10, the opposite sides of which project at substantially right angles.

Formed in one of the sides are a series of openings 11 provided for the reception of suitable fastening means, such as screws 12 or the like. In applying the angular members 10 to the cover 2, the cover is preferably mortised along the opposite edges thereof, as indicated at 12, so that when the members 10 are secured in position therein the under surfaces of the sides 13 will lie flush with the under side of the cover and form a tight closure coöperating with the upper edge of the box. When so applied, the sides 14 of the locking members project away from the cover in such position as to fit snugly into the channels or grooves 7 formed between the main body of the box and the inner lining. If desired, supplemental angular members 15 may be secured to the cover so as to constitute continuations of the locking members 10. The downwardly projecting sides of the members 10 and 15 are preferably formed with precision faces and project downwardly a distance substantially equal to the thickness of the precision surface secured to the under side of the cover. Due to this construction constant removing and positioning of the cover, although tending to wear the edges 16 of the precision surface, do not prevent the same from being used with precision instruments, such as a T-square or the like, in the manner illustrated in the drawings. When the supplemental members 15 are omitted, the locking members 10 receive the precision instruments throughout their own length and the edge of the precision surface throughout the unprotected portion thereof.

In the ends of the projecting sides 14 are formed curved open ended locking grooves 40 or recesses 18 adapted to coöperate with the elongated convex bearing surfaces 19 formed on the bearing members 20. Due to the particular construction of the locking grooves it will be apparent that when the cover is in closed position vertical movement thereof will be prevented. Upon swinging the cover from its closed position the locking members may be readily separated as indicated clearly in Fig. 1 of the drawings.

It is usually desirable to have the bearing members extend longitudinally of the box and for this purpose the same is provided with depressions or mortises 21 in which the same may be secured.

In some instances, however, it may be found advantageous to employ bearing members 22 adapted to extend vertically of the box. Members of this type are illustrated in detail in Fig. 8 of the drawings and may be secured in position by mortising the box as described in connection with the bearing members 20.

In Figs. 7 and 9 of the drawings I have illustrated locking members 10 having formed in the ends thereof angular or offset

portions 24 forming an open-ended groove or recess therebetween, said portions and recess being adapted to coöperate in locking relation with oppositely formed projections and grooves or recesses on the bearing members 25.

It will be obvious that when any of the forms of locking members already described are employed, it will be impossible to remove the same when the box cover is in closed position, as the fastening means are entirely concealed within the box.

In Fig. 10 I have illustrated a form of locking member which may be used exteriorly or interiorly of the box for certain purposes. This form comprises a vertical web 26 having fastening openings 27 formed therein and provided with a curved or angular open ended locking groove or recess 28. The locking groove is adapted to receive and coöperate with a similarly formed bearing 29 on the block 30. When this type of locking member is employed it may be provided with a stop 31 operatively contacting, when the lid is in closed position, with the abutment surface 32. It will be understood that in use the locking members may be readily moved from their dotted interlocked position shown in the drawings to the full line position illustrated.

I am aware that it has heretofore been proposed to employ various types of detachable hinges for use in connection with boxes, storm shutters, transoms, and the like, but such constructions cannot be used with a kit of the present nature for the reason that a portion of the locking means would project beyond the exterior surface thereof or would be secured exteriorly of the same so that they might be readily removed.

In actual practice the interior of the kit may be divided into any suitable number of individual compartments adapted for the reception of writing materials, a field typewriter, or the like. When it is desired to do any writing or field work not requiring the use of a precision surface, the upper side of the lid may be employed as a desk, the under side being reserved for precision drafting, sketching, or equivalent uses.

It will be apparent that changes may be made in the preferred embodiment of my invention illustrated in the drawings, within the scope of the appended claims, without departing from the spirit thereof.

What I claim is:

1. A reversible cover for field kits, comprising an upper working surface, a projecting precision surface on the lower side thereof, a precision edge for said surface, and a detachable locking joint formed in said edge.

2. A reversible cover, comprising an upper working surface, a projecting precision surface on the lower side thereof, an angu-

lar precision edge for said surface, and a detachable locking joint formed in one portion of said edge.

3. A detachable locking connection for 5 removable covers, comprising an angular member adapted to be secured to the underside of said cover and project downwardly therefrom, a locking groove formed therein, and a bearing member adapted to 10 operate therewith.

4. A detachable locking connection for removable covers, comprising an interlocking strip adapted to be secured to the said cover and project downwardly therefrom, 15 said strip having an open ended locking recess formed in one end thereof, and a bearing member adapted to detachably coöperate with said recess.

5. A detachable locking connection for 20 removable covers, comprising an interlocking strip having a precision edge adapted to be secured to the said cover and project downwardly therefrom, said strip having an open ended locking recess formed in one end 25 thereof, and a bearing member adapted to detachably coöperate with said recess.

6. A combined precision edge and locking member for removable covers, comprising an angular body portion having fastening 30 openings formed in one side thereof, and an open ended locking recess formed in the opposite side thereof.

7. A reversible cover, comprising upper

and lower projecting members, and a precision interlocking edge partially surrounding one of said members. 35

8. A reversible cover, having projecting members secured to opposite sides thereof, and a precision edge coöperating with one of said members, said precision edge having 40 a detachable locking groove formed in one end thereof.

9. A detachable connection for removable covers, comprising a bearing member, a bearing surface formed thereon, a second 45 member adapted to be secured to said cover in projecting relation thereto, and an open ended bearing surface formed in one end of said member adapted to coöperate detachably with said first mentioned bearing surface. 50

10. A reversible cover for field kits, comprising an upper working surface, a projecting precision surface on the lower side thereof, a precision edge for said surface, 55 and an open ended detachable locking recess formed in said edge, substantially as described.

11. A reversible cover comprising an upper working surface, a projecting precision 60 surface on the lower side thereof, an angular precision edge for said surface, and an open ended detachable locking recess formed in one portion of said edge, substantially as described.

JOSEPH W. McCANN.
